UNITED STATES PATENT OFFICE.

JOHN A. QUIRK, JR., OF JERSEY CITY, NEW JERSEY.

LOCK.

1,145,265.

Specification of Letters Patent.

Patented July 6, 1915.

Application filed August 14, 1912. Serial No. 715,091.

To all whom it may concern:

Be it known that I, JOHN A. QUIRK, Jr., a citizen of the United States, residing at Jersey City, in the county of Hudson and 5 State of New Jersey, have invented new and useful Improvements in Locks, of which the following is a specification.

My invention relates to locks such as are used to lock a wheel of a vehicle against 10 movement so as to prevent the use of the vehicle by an unauthorized person.

The object of the invention is to provide a novel and efficient form of lock adapted to be operated by a key to unlock the same, and 15 which may be automatically locked and without the use of the key.

A further object of the invention is to provide a member adapted to be inserted into the lock and means consisting of a 20 latch adapted to lock said insert member.

A still further object of the invention is to provide such a lock as set forth, which is mounted in a box or the like so that it may be readily secured to a wagon or other vehicle. 25

The preferred embodiment of my invention is hereinafter described and illustrated in the accompanying drawings.

In these drawings, Figure 1 is a view 30 partly in elevation and mostly in section. Fig. 2 is an end view. Fig. 3 is a detail of the latch-retracting member. Fig. 4 is a detail of the latch, and, Fig. 5 is a detail of the head of the insert bolt member.

Referring to the drawings, 1 designates 35 a box supporting the parts of the lock and from which extend suitable ears or the like 2, through which may be passed bolts such as 3 to secure the box to the wagon body or other support. Into the box 1 is screwed an eye-bolt 4 having attached thereto a chain or the like 5, which chain 5 is also attached to an insert eye-bolt 6 having a rod portion 7 adapted to be inserted in an opening 8 provided in the box 1. The rod portion 7 at 40 its outer end, is cut away to form a circumferential groove 9 and a head 10.

The numeral 11 designates a turnable or rotatable latch operating member. Said 45 member is provided with a circumferential groove 12 into which extends a positioning or set screw 13 which passes through a portion of the box 1. The set screw 13 permits rotary or turning movement of the member 11 but prevents longitudinal movement thereof. Said member 11 operates in a slot

14 in the box 1, and a latch bolt 15 which is actuated by said member also moves in said slot 14. The actuating member 11 is provided with a hollow portion or slot 16 into which is adapted to extend the shank or rod 17 of the latch 15. An enlarged slot having an inclined or cam wall 18 is provided in the actuating member 11, and in said slot works a pin 19 secured on the rod 17 and holding said rod and member 11 in engagement. A spiral spring 20 surrounds the rod 17 and is interposed between the end of the actuating member 11 and the head 21 of the latch. Said head 21 of the latch has a shoulder 22 adapted to abut against a wall of the box to limit its longitudinal movement and is also provided with a tongue 23 to enter the circumferential groove 9 of the insert eye-bolt member, and to engage under the head 10 to normally prevent removal of said insert eye-bolt member. The latch actuating member 11 is provided with a suitable groove or grooves 24 adapted to be engaged by bits of a key 25.

The device described and illustrated is principally adapted to be attached to the body of a wagon. The wagon when left alone by the owner is adapted to be locked by the device, the owner of course, possessing the key 25 to unlock the wagon. When the wagon is locked, the eye-bolt member 6 is disengaged from the box 1 and is passed through a wheel of the wagon and around the rim of said wheel, and the rod portion 7 is inserted into the slot 8 and pressed against the tongue 23, whereupon said tongue yields away from the head 10 until said head 10 has passed the same, whereupon the spring 20 will return the tongue to its normal position and into the groove 9 and beneath the head 10.

When the eye-bolt 6 is to be removed from locked position so as to free the wheel, the key 25 is inserted into the openings 24 of the latch actuating member 11, and then turned so as to turn the actuating member 11. By the turning movement the inclined wall 18 operates against the pin 19 and retracts the same from engagement with the groove 9, under the head 10 of the insert eye-bolt, whereupon said eye-bolt is free to be withdrawn. After disengagement of said insert eye-bolt the key 25 is withdrawn and the spring 20 restores the latch bolt to its normal position, so that when it is desired to again insert the eye-bolt member 6 into

the box to lock a wheel, the head 10 will engage and automatically force away the latch until the head 10 has passed the same, whereupon the spring 20 will move into the groove 9 and again lock the eye-bolt 6 in the box 1, and accordingly the wheel through which it is passed, is locked against rotation.

It is clear that changes in the details of construction of the device may be made without departing from the spirit and scope of the appended claims.

Having thus described my invention, what I claim is:

1. In a device of the class described, a box, a latch member, a latch actuating member, said latch actuating member having a bore formed therein, a rod formed on said latch member and disposed within said bore, said actuating member having a cam slot formed therein, a pin formed on said rod and extending into said cam slot, a bolt for engagement with said latch, and means to

normally hold said latch in engagement with said bolt.

2. In a device of the class described, a box, a chain fastened to said box, a member insertible into said box and adapted to be passed through an object to be locked, said chain connected to said member, a slideable latch, said member having a head to engage said latch, said latch having a rod portion, a pin projecting from said rod portion, a turnable actuating member for said latch provided with a slot having a cam wall and into which said pin extends, a spiral spring surrounding said rod portion and bearing against said latch and said turnable member, said turnable member provided with a groove, and a positioning member passing through said box and entering said groove.

JOHN A. QUIRK, JR.
